UNITED STATES PATENT OFFICE.

ADALBERT HERMANN, OF VIENNA, AUSTRIA-HUNGARY.

DEVICE FOR REMOVING WATER FROM LAYERS OF ARTIFICIAL-STONE PULP.

1,083,279.

Specification of Letters Patent.

Patented Jan. 6, 1914.

Application filed May 20, 1911. Serial No. 628,395.

To all whom it may concern:

Be it known that I, ADALBERT HERMANN, a subject of the Emperor of Austria-Hungary, residing at Vienna, Lower Austria, Empire of Austria-Hungary, have invented certain new and useful Improvements in Devices for Removing Water from Layers of Artificial-Stone Pulp, of which the following is a specification.

10 This invention relates to improvements in devices for removing the water contained in the layer formed upon an endless metallic cloth from a relatively thick pulp of hydraulic binding media, for example cement 15 and fiber, such as asbestos, used in the manufacture of articles made of artificial stone. When employing such a thick pulp consisting for example of about 300 kg. of dry substances and 4000 l of water it has been 20 found that the comparatively large content of specifically heavy dry substances at once causes deposition of the latter, whereby the water contained in the pulp rises, so that a removal of the water downward as customary 25 in the manufacture of paper or pasteboard is impossible.

The object of my invention is to provide means for the removal of the water from the surface of the layer formed upon the metallic cloth.

In the accompanying drawing Figure 1 represents a side elevation of that part of a machine for the manufacture of plates of artificial stone, in which the device for the removal of the water is arranged. Fig. 2 represents another mode of execution of this device.

In the drawing *a* designates part of an endless metallic cloth guided over cylinders, 40 the rear one of which is shown and indicated by *b*.

c is the lever formed by feeding the pulp to the metallic cloth *a* in a suitable place; during the movement of the metallic cloth *a* 45 the heavy dry substances of the layer settle, the water being thereby caused to rise. *h* is an impermeable plate. For carrying off this water there is arranged before the cylinder *b* an endless ribbon *d* of felt or the like 50 sucking material moved with the same velocity as the metallic cloth and directed toward the surface of the layer by the roller *e*, this ribbon lying on the surface of the layer by reason of its own weight and being 55 conducted together with the metallic cloth

and the layer under high tension around the cylinder *b*. Below the cylinder *b* a further cylinder *f* is arranged pressing against cylinder *b* and around this cylinder *f* the endless ribbon *d* passes carrying with it the 60 layer for feeding the latter to a well known winding up device not represented in the drawing. From the cylinder *b* the endless metallic cloth returns to the feeding place.

The operation of the device is as follows:— 65 The water on the surface of the layer is partly sucked off by the ribbon *d* before the cylinder *b* is reached by the ribbon *d* and the tension of this ribbon on cylinder *b* produces a pressure upon the layer and 70 causes the water still remaining in the layer to be pressed out toward the ribbon *d*, this latter being simultaneously squeezed, thereby a continual removal of the water being secured. Over the cylinder *f* the homogeneous layer nearly freed from water is 75 conveyed upon the ribbon *d* to the winding up device while the metallic cloth returns to the feeding place.

To increase the sucking capacity of the 80 ribbon *d* a second ribbon *g* of felt like sucking material may be arranged in close proximity above the ribbon *d*, as shown in Fig. 2, which second ribbon *g*, moved with the same velocity as ribbon *d*, takes up from the 85 same part of the pulp water already sucked off thereby.

What I claim is:

1. In a device for removing water from layers of an artificial stone pulp, the combination of an endless metallic cloth running over an impermeable plate and a cylinder and carrying the layer in advance of the cylinder with a ribbon of a sucking material lying upon the surface of the layer and 90 guided together with the metallic cloth and the layer around the said cylinder under tension, substantially as described.

2. In a device for removing water from layers of an artificial stone pulp, the combination of an endless metallic cloth running over an impermeable plate and a cylinder and carrying the layer in advance of the cylinder with a ribbon of a sucking material lying upon the surface of the layer and 95 guided together with the metallic cloth and the layer around the said cylinder under tension and a second cylinder arranged below the first cylinder and pressed against it, the ribbon together with the layer passing over 100

105 the second cylinder and being conducted together with the metallic cloth and the layer around the second cylinder under tension and a second cylinder arranged below the first cylinder and pressed against it, the ribbon together with the layer passing over 110

the said second cylinder, the metallic cloth being separated from the layer, substantially as described.

3. In a device for removing water from layers of artificial stone pulp formed on an endless, movable metallic cloth, a ribbon of a sucking material conveyed close to the surface of the layer in combination with a second ribbon of a sucking material conveyed close over and with the same velocity as the first ribbon and arranged to suck from the latter a part of the water absorbed by the same from the layer, substantially as described.

4. In a device for removing water from layers of artificial stone pulp, the combination of an endless metallic cloth running over an impermeable plate and a cylinder and carrying the layer in advance of the cylinder with a ribbon of a sucking material lying upon the surface of the layer and guided together with the metallic cloth and the layer around the said cylinder under tension and a second ribbon of a sucking material conveyed close over and with the same velocity as the first ribbon and arranged to suck from the latter a part of the

water absorbed by the same from the layer, substantially as described.

5. In a device for removing water from layers of artificial stone pulp, the combination of an endless metallic cloth running over an impermeable plate and a cylinder and carrying the layer in advance of the cylinder with a ribbon of a sucking material lying upon the surface of the layer and guided together with the metallic cloth and the layer around the said cylinder under tension, a second cylinder arranged below the first cylinder and pressed against it, the ribbon together with the layer passing over the said second cylinder, the metallic cloth being separated from the layer, and a second ribbon of a sucking material conveyed close over and with the same velocity as the first ribbon and arranged to suck from the latter a part of the water absorbed by the same from the layer, substantially as described.

In testimony whereof I affix my signature in presence of two witnesses.

ADALBERT HERMANN.
